CLAIM

The ornamental design for an ultrasonic applicator, as shown and described.

DESCRIPTION

FIG. 1 is a front elevational view of a first embodiment of an ultrasonic applicator of my new design, the rear elevational view being the mirror opposite thereof;

FIG. 2 is a right side elevational view thereof; the left side elevational view being the mirror opposite thereof;

FIG. 3 is a top plan view thereof;

FIG. 4 is a bottom plan view thereof;

FIG. 5 is a front elevational view of a second embodiment of an ultrasonic applicator of my new design, the rear elevational view being the mirror opposite thereof;

FIG. 6 is a right side elevational view thereof, the left side elevational view being the mirror opposite thereof;

FIG. 7 is a top plan view thereof; and,

FIG. 8 is a bottom plan view thereof.
